FIG. 4

Des. 222,085

PAGE 4

FIG. 6

FIG. 1 is a perspective view of a storage rack for clothes hangers embodying my new design.

FIG. 2 is a top plan view thereof.

FIG. 3 is a left side elevation thereof, the right side being a mirror image of the left side as shown.

FIG. 4 is a front elevation thereof.

FIG. 5 is a rear elevation thereof.

FIG. 6 is a bottom plan view thereof.

I claim:

The ornamental design for a storage rack for clothes hangers, as shown and described.
